UNITED STATES PATENT OFFICE.

OTIS A. KITTINGER, OF SAN ANSELMO, CALIFORNIA.

ROTATING SPRINKLER.

Application filed February 6, 1926. Serial No. 86,451.

This invention relates to sprinkling devices, and more particularly to lawn sprinklers of the revolving type adapted to utilize the water pressure to throw the water 5 radially of the support. In such devices the water is usually thrown in a circular path, the outermost limit of throw being the circumference of a circle circumscribed about the axis of the support as a center, it 10 being assumed that the rotor is parallel to the space being sprinkled.

Many lawns, flower beds, gardens, etc., are of rectangular formation and, if sprinklers such as above referred to are utilized 15 in such formations, the extreme corners of the plots will not be reached by the water, when the power is only sufficient to project the latter to the sides of the plot. If greater power is applied the corners may 20 be reached, but the water will be thrown beyond the sides of the rectangular formation, resulting in needless waste, as will be readily understood.

The present invention is an improvement 25 upon the structure set forth in my co-pending application filed May 26, 1924, Ser. No. 715,947, in so far as is concerned the means for causing rotation of new and improved 30 sprinkler arms, and in the particular configuration of the openings in the stationary reservoir, which openings govern the amount of water to be received by the said arms.

The object of the present invention therefore 35 is the provision of a new and improved sprinkler of the general rotating type referred to, equipped with improved means adapted to distribute the water over a surface of rectangular formation.

40 Other objects of the invention will be made apparent in the following specifications, when read in connection with the accompanying drawings.

In said drawings:

45 Fig. 1 is a fragmentary vertical section taken through my improved sprinkler.

Fig. 2 is a fragmentary section of the sprinkler, on the line 2-2 of Fig. 1.

50 Fig. 3 is a perspective view showing the stationary reservoir.

Fig. 4 is a diagrammatic top plan view of the sprinkler in operation, the arrows indicating the maximum and minimum throw of the water.

Fig. 5 is a schematic detail illustrating 55 the operation of the control which regulates the distance of the water throw.

Fig. 6 is a side elevation of the sprinkler mounted for operation.

Fig. 7 is a plan view of the side wall of 60 the reservoir in flattened condition, or stretched out and,

Fig. 8 is a perspective view of the outer end of one of the sprinkler arms.

Now referring specifically to the drawings, A is a supply pipe adapted to deliver water under pressure, said pipe being mounted upon a standard A', the lower end of said pipe being in communication with a flexible hose A², or otherwise connected to a 70 water supply, see Fig. 6.

To the top of the pipe A is rigidly and nonrotatively secured a reservoir 1, open at the top and having a circular side wall 2, and a bottom 3, centrally apertured to receive the end of the pipe A.

The wall 2 of the reservoir 1 describes a circle, and extending through each quadrant of said circle is an opening or aperture 4 of the configuration clearly illustrated in the stretch-out of the wall 2, shown in Figs. 5 and 7. All of the apertures 4 are symmetrically formed, but every two adjacent apertures are reversed, each having an elongated base or top 5, as the case may be, 85 by position, and an apex 6 formed on a line parallel to the base or top 5. Rising from the base 5, to approximately one-third of the distance from the apex 6, are straight sides 7, forming a right angle with the base, 90 and gradually curved lines 8 connecting the sides 7 with the apex 6. It is to be noted that, as shown in Figs. 5 and 7, the side 7 of one aperture is in exactly the same vertical plane as the side 7 of the adjacent aperture, although the two apertures lie in different horizontal planes. The apertures need not be reversed as shown in Figure 7, but this is the preferred embodiment because the resulting reservoir is of very rigid 100 construction.

As illustrated in Fig. 1, the top portion of the pipe A is somewhat enlarged at A². A shell B surrounds the reservoir 1, and is slightly spaced therefrom to permit free rotation, and the lower portion of the shell B is provided with a reduced depending sleeve 9 which encircles said portion A², the sleeve 105

being connected to the body of the reservoir by a wall 10, provided with a raceway for anti-friction balls 11, the upper portion of said balls bearing against the lower surface of the floor 3 of the reservoir, when the sprinkler is in operation. Concentrically surrounding the sleeve 9 is a collar 9' which is screw-threaded to said sleeve 9 and rotatable therewith, the lower periphery of said collar being turned inwardly to support a packing gasket 9'', located adjacent the lower periphery of the sleeve 9, the structure just described forming a sufficiently effective stuffing box in preventing too great a waste 10 of water, and permitting rotation of the sleeve 9, carried by the shell B.

The shell B carries a plurality of sprinkler arms 12, 12 and 13, 13, here shown as arranged in pairs. Each arm extends radially 20 of the shell B, the arms 12, 12 being diametrically opposed, and the arms 13, 13 being likewise positioned thereon. The outer end of each arm is provided with a hollow head 14, carrying a plurality of orifices 15 25 in its outer face, and an orifice 16 in its side face.

The inner end of each arm 12 and 13 communicates with the interior of the shell B through a relatively thin, vertically-extending slot 17, of a height equal to the distance 30 between the apex 6 and the base 5 of the apertures 4 in the reservoir 1. A cover 18 screw-threads onto the top of the shell B.

With the instrumentalities assembled as 35 herein set forth, when the water is turned on, the force thereof causes the shell B to ride upwardly on the portion A² of the pipe A, the reservoir 1 being filled with water, and the latter passing through the apertures and 40 through the slots 17 into the arms 12 and 13, and out through the orifices 15 and 16 in the head 14. The force of the water expelled 45 through the orifice 16, in the side of the head 14, operates along the principle of the well known Barker's mill, and causes a rearward movement of the arms 12 and 13, and hence a rotation of the shell B, around the reservoir 1, the speed of rotation being dependent upon the pressure of the water led into the 50 reservoir. The water expelled from the orifices 15 is thrown outwardly away from the rotating arms 12 and 13, while the water emitted from the orifice 16 sprinkles the formation adjacent the sprinkler.

55 The water is sprinkled over a rectangular formation, as indicated in Fig. 4. As the water under pressure enters the arms 12 and 13, it is ejected through the orifices 15 a distance which is directly proportionate to the 60 amount of pressure upon the water within the arm. Manifestly, the amount of water passing through each arm governs the pressure therein, and the volume of water allowed to directly enter each arm is dependent upon the extent to which the inner or

receiving end of the arm, that is slot 17, is in direct registration with one of the apertures 4.

In Fig. 5 is a schematic imaginary showing 70 of a slot 17 of an arm 12 passing laterally over an aperture 4, the four apertures being indicated as 4^a, 4^b, 4^c and 4^d, the slots 17 being shown in dotted lines, and the distance the water is thrown being indicated in full lines. As the front portion of the slot 17 first 75 comes into registration with the aperture 4^c, the water throw is minimum, and this throw is determinable to a very fine degree, dependent upon the area of the slot in registration with the aperture, because the vertical slot 17 is presented laterally to the aperture 4^c, past the side wall 7 of the latter. At the outset, when the front edge of the slot moves past the wall 7, only the lower portion of the vertical height of the slot is in registration with 80 said aperture, such portion being of the length of the wall 7, as will be understood. Moreover, until the slot has moved further towards the center of the aperture 4^c only 85 the front side of the lower portion of the slot is in communication with said aperture, or that portion which has passed the wall 7, and only a small volume of water is passing directly from the aperture to said arm, 90 said volume gradually increasing in direct proportion to the extent of travel of said slot towards the center of said aperture, or until the entire lower portion of the slot passes the wall 7, as will be understood. From the 95 foregoing it will be understood that the distance to which the water is thrown increases, at the outset, from minimum, until the slot 17 is in complete registration with the aperture 4^c. The curved wall 8 defines the continued and uninterrupted increase thereafter, 100 since continued movement of the slot 17 towards the center of the aperture 4^c causes the gradual exposure, to the aperture, of an additional length of the slot 17, such additional registration permitting gradually increasing 105 volumes of water under pressure to enter the arm 12, resulting in the water being thrown a gradually increasing distance from the orifices 15.

As the slot 17 reaches the center of the 115 aperture 4^c, the entire length thereof is in registration with the aperture 4^c, and the maximum amount of water is being thrown from the orifices 15, during the passage of 120 said slot over the space defined by the apex wall 6. Continued movement of the slot 17 to the right results in a gradual decrease of 125 the supply of water, since the curved wall 8 at the right of the aperture gradually shuts off the supply to the upper portion of the slot, and the latter finally passes the lower wall 7 at the right of the slot, the supply of water from the aperture 4^c being 130 in this manner gradually decreased and finally shut off.

It is to be here again noted that the apertures 4 are arranged in each quadrant of the circle defined by the wall 1, and that, as shown in the drawings, the elongated portion of the aperture, bounded by the walls 7, 5 is at the top in one quadrant, and at the bottom of the quadrant next adjacent thereto. Attention is also called to the fact that the wall 7 of the one aperture 4, and the 10 wall 7 of the adjacent aperture 4, are in direct vertical alignment, although located in different horizontal planes, as clearly seen in Figs. 3, 5 and 7. Consequently, when the water from the one aperture 4 is automatically 15 cut off from the slot 17 by one of the walls 7, the slot 17 co-incidently passes the wall 7 of the adjacent aperture 4, and initiates a throw of water of the same volume and under the same power. In other words, 20 and now referring to Fig. 5, when the slot 17 passes entirely out of registration with the aperture 4^a, at minimum throw, it simultaneously passes into registration with aperture 4^d, also at minimum throw, the operation as set forth being continuously repeated 25 as long as the shell B rotates.

In the diagrammatic view shown in Fig. 4, the points *x* and *z* indicate the minimum distance to which the water is to be thrown, 30 and the point *y* indicates the corner of the rectangle, or the maximum distance. As the slot 17 (Fig. 5) is being closed by the wall 7 of aperture 4^e, the throw is minimum, or to the point *x*, Fig. 4. Immediately the slot 17 35 passes into registration with the aperture 4^d, and, without interruption, the water passing through said aperture into said slot 17 is thrown by the arm 12 to the point *x*, the distance gradually increasing until the 40 point *y* is reached, and thence decreasing until the point *z* is reached, whereupon the water from aperture 4^d is cut off from said arm 12 and the aperture 4^a commences to feed the water to the arm, as heretofore explained. 45

It is to be understood that, in the construction herein disclosed, as each of the arms 12, 13, 12, 13, passes one of the apertures 4, the arm throws water first to the 50 point *x*, thence gradually increasing the distance to the point *y*, and thence decreasing the distance to the point *z*, where the adjacent aperture 4 takes up the feed to the slot 17. In order to reach the corner, the curved 55 portion of each aperture is a little more than one and one-half times the height of the rectangular portion. Applicant has evolved a formula for determining this relation which may be briefly stated as "the length of the 60 orifice varies as the cube of the distance from the sprinkler to the edge of the figure to be covered." The curves of the upper portion of the aperture are preferably graphically determined by plotting, the geometrical figure 65 to be sprinkled and the necessary aperture

ture opening for covering each section of the geometrical figure, varying proportionately. The theoretical curves, however, must be modified in accordance with actual experiment, as the inertia of the water makes 70 slight changes necessary. Thus, the apex is theoretically a point, but actual tests show that it must be of appreciable extent in order to permit the water to reach the corners. 75

Considering each aperture, the lower rectangular portion, formed by the walls 7, permits the sprinkling of a circle, while the arcuate portion formed by the walls 8 permits the sprinkling of the area between this 80 circle and the boundary of the rectangular figure. The apertures 4 may thus be considered as comprising two sections or openings, one for permitting the sprinkling of a circle inscribed within a square or rectangle, which circle may be called a base circle and the other for permitting the sprinkling of the corner spaces between this base circle and the square or rectangle. The construction illustrated and described is designed for 85 sprinkling square areas. Obviously, this teaching may be employed for sprinkling any straight sided geometrical area, the necessary structural modifications being within 90 the scope of my invention. 95

From the foregoing it will be noted that I have provided a sprinkler structure which is adapted to automatically throw water over a rectangular formation, and in which there is no cessation of the flow. In my co-pending application heretofore referred to the circumferentially-elongated openings were in the same horizontal plane around the ring, resulting in a space between the openings, and causing a somewhat irregular 100 spread of water while the sprinkler arms were passing from one opening to another. In the present structure the arm receives water from the aperture co-incidently with the stoppage of the supply of water from 105 the other arm, and consequently there is no variation in the force of the water. The structure of the shell B is also strengthened, because, by placing the apertures in different horizontal planes, the solid portion of 110 the shell between the apertures may be left as required for the necessary strength. By carefully measured constructions, after geometrical calculations, the present structure can be so formed as to enable it to sprinkle 115 a rectangular formation in lines which are almost exactly straight, in the absence of any wind. 120

When the device is out of operation the lower surface of the cover 18 rests upon 125 the upper periphery of the reservoir 1, retaining the shell against downward movement on the pipe section A². As soon as the water is turned on the pressure against the lower face of the cover 18 operates to 130

raise it out of contact with the upper periphery of the reservoir 1, as shown in Fig. 1.

Modifications of the structure herein described may be suggested to those skilled in the art, but my invention covers all modifications falling fairly within the scope of the appended claims.

What I claim is:

- 10 1. A circular reservoir for use with rotating sprinklers for sprinkling a straight sided geometrical area, having a periphery provided with openings shaped and positioned for sprinkling a base circle, and openings shaped and positioned for sprinkling 15 the corner areas between the periphery of said geometrical area and said base circle.
- 20 2. A circular reservoir for use with rotating sprinklers for sprinkling a straight sided geometrical area, having a periphery provided with apertures comprising openings shaped and positioned for sprinkling a base circle and additional openings shaped and positioned for sprinkling the corner areas between the periphery of said geometrical area and said base circle.
- 30 3. A circular reservoir for use with rotating sprinklers for sprinkling a square area, having a periphery provided with openings shaped and positioned for sprinkling a base circle, and openings shaped and positioned for sprinkling the corner areas between the periphery of said square area and said base circle.
- 35 4. A circular reservoir for use with rotating sprinklers for sprinkling a square area, having a periphery provided with apertures comprising openings shaped and positioned for sprinkling a base circle and additional openings shaped and positioned 40 for sprinkling the corner areas between the

periphery of said square area and said base circle.

5. A sprinkler comprising a fixed reservoir in communication with a supply of water under pressure, a circular shell rotatably mounted concentrically of and immediately adjacent the outer side of said reservoir, at least one hollow sprinkler arm carried by the periphery of said shell and opening into the interior of the shell, and apertures in the periphery of the reservoir permitting communication of the arm or arms with the interior of the reservoir for sprinkling a square area, said apertures comprising openings shaped and positioned 55 for sprinkling a base circle, and additional openings shaped and positioned for sprinkling the corner areas between the periphery of said square area and said base circle.

6. A sprinkler comprising a fixed reservoir in communication with a supply of water under pressure, a circular shell rotatably mounted concentrically of and immediately adjacent the outer side of said reservoir, at least one hollow sprinkler arm carried by the periphery of said shell and opening into the interior of the shell, and apertures in the periphery of the reservoir permitting communication of the arm or arms with the interior of the reservoir for sprinkling a straight sided geometrical area, said apertures comprising openings shaped and positioned for sprinkling a base circle, and additional openings shaped and positioned for sprinkling the corner areas between the periphery of said geometrical area and said base circle.

In testimony whereof I affix my signature.

OTIS A. KITTINGER.
